(57) **CLAIM**

The ornamental design for a faucet, as shown and described.

DESCRIPTION

FIG. 1 is a front perspective view of a faucet showing my design;

FIG. 2 is a front elevational view thereof;

FIG. 3 is a rear elevational view thereof;

FIG. 4 is a left side elevational view thereof; the right side elevational view being a mirror image thereof; and,

FIG. 5 is a top plan view thereof.

The broken lines in the figures are included for the purpose of illustrating portions of the faucet that form no part of the claimed design.
